UNITED STATES PATENT OFFICE

JOSEPH SACHS, OF HARTFORD, CONNECTICUT

FUSE BLOCK ATTACHMENT

Application filed June 3, 1926. Serial No. 113,492.

In meter service installations it is common to provide an electrical connecting and circuit controlling appliance by means of which the circuit to the meter and the connected load may be properly connected and controlled by manual operation as well as automatically by means of fuses. Such connecting and controlling devices have been incased in a suitable housing provided with means for its protective relation and placement in connection with the meter itself. The housing is usually sealed so that the devices inside of it are inaccessible except by breaking the seal, thus providing security against tampering and unauthorized manipulation or connection with the circuit ahead of the meter.

In conjunction with installations such as described, it is frequently desirable to provide devices or attachments adapted to be carried by or directly associated with the housings or cabinets and adapted for holding auxiliary fuses in position to be accessible to the customer from the outside of the cabinets and also adapted for the connection of branch circuit wires in series with the fuses. The present invention relates particularly to devices or attachments of this general character, although as to some of its features it is not so limited.

A device or attachment of the type to which the invention more particularly relates comprises a body, ordinarily of insulating material, secured to or adapted to be secured to or immediately adjacent one wall of the cabinet so as to at least partly close an opening therein. Carried by the block in position to be accessible externally of the cabinet are complementary contacts for receiving and holding one or more fuses. One or more terminals respectively connected with the fuse receiving means are carried by the block so as to extend through the said opening in the wall and to be available for establishing a connection with the load side of the circuit controlling appliance inside of the cabinet, and one or more other terminals respectively connected with the fuse receiving means in series with the first said terminals are positioned for connection with conductor wires

ordinarily forming parts of branch circuits.

A very simple form of device of the class described is shown in my patent for incased circuit connecting and controlling device, No. 1,465,688, dated August 21, 1923. As disclosed in this patent, each device or attachment is provided with means for holding a single fuse and both of the terminals are so located as to be accessible only from the interior of the cabinet.

Another device of the same general type is disclosed in my patent for inclosed switch attachment, No. 1,597,484 dated August 24, 1926. The device as shown in this later patent embodies several improvements over the device as shown in the earlier patent. Instead of being adapted for holding only a single fuse, it is adapted for holding a plurality of fuses, and it is provided with terminals whereby a single device can serve for providing fuse connections for both legs of a branch circuit. Furthermore, the device as shown in the later patent is particularly constructed so as to be adapted to be located in an open-side or U-shaped opening such as is commonly provided in a meter service cabinet.

A device embodying the present invention is of the type already described and already exemplified by the devices shown in the said patents. In accordance with the invention, however, several important improvements are incorporated as will presently appear.

One object of the invention is to provide as a part of the attachment one or more continuous terminals, which may be flexible wires, and which are permanently connected with the fuse receiving means on the attachment so as to be adapted to extend into the cabinet for connection directly to conducting parts of the circuit controlling appliance within the cabinet, thus eliminating the necessity for using separate conductor wires for electrically connecting the attachment to the appliance.

A further object of the invention is to provide one or more terminals connected with the fuse receiving means and so located as to be accessible from the outside of the cabinet and adapted for the direct connection of con-

ductor wires located entirely outside of the cabinet.

A still further object of the invention is to provide improved means for connecting the attachment to the cabinet with which it is associated.

Additional objects of the invention will be apparent from the drawings and from the following specification.

10 In the drawings I have illustrated several of the many possible embodiments of the invention, but it is to be understood that these embodiments of the invention are shown merely for purposes of illustration and are 15 not to be construed as defining or limiting the scope of the invention, the claims forming a part of the specification being relied upon for that purpose. It will be further understood that the invention may be embodied in an attachment as a separate unit or in the combination 20 of a cabinet and its contained appliance with an attachment.

Of the drawings:

Fig. 1 is a front view showing a part of a 25 meter, a cabinet associated with the meter and having a circuit controlling appliance therein, and a fuse block attachment embodying the invention, the front covers for the cabinet and the attachment being omitted.

30 Fig. 2 is a side view of the parts shown in Fig. 1, but with the covers included.

Figs. 3 and 4 are respectively top and front views on an enlarged scale and showing one form of block which may be used.

35 Figs. 5 and 6 are views similar respectively to Figs. 3 and 4, but showing a somewhat different block.

Fig. 7 is a front view on an enlarged scale 40 showing the attachment separately from the cabinet.

Figs. 8 and 9 are vertical sectional views taken respectively along the lines 8—8 and 9—9 of Fig. 7, the block being of the form shown in Figs. 5 and 6.

45 Fig. 10 is a detail view showing a disk for holding the flexible terminal conductors.

Fig. 11 is a perspective view of the complete attachment as a separate unit.

50 Fig. 12 is a fragmentary view similar to Fig. 1, but showing a different wiring connection.

Fig. 13 is a fragmentary view similar to Fig. 1, but showing an attachment adapted for use with two, instead of four, branch circuits.

55 Fig. 14 is a perspective view similar to Fig. 11, but showing the attachment appearing in Fig. 13.

60 Fig. 15 is a front view similar to Fig. 1, but showing a different fuse block attachment embodying some of the features of the invention.

Fig. 16 is a side view of the parts shown in 65 Fig. 15.

Fig. 17 is an enlarged front view of the attachment shown in Figs. 15 and 16.

Fig. 18 is a horizontal sectional view taken along the line 18—18 of Fig. 17.

Fig. 19 is a fragmentary sectional view taken along the line 19—19 of Fig. 17.

As already stated, an attachment embodying the invention is adapted for use with an electric appliance receiving cabinet, particularly a cabinet adapted to be protectively 75 associated with a meter and containing a meter circuit controlling appliance. As concerns the details of the meter service equipment I do not in any way limit myself but for the purposes of illustration I have shown 80 in Figs. 1 and 2 one form of equipment which may be used. As illustrated, there is a cabinet 1, preferably formed of sheet metal, and having a back wall 2, side walls 3, 3, a bottom wall 4, a top wall 5 and a movable cover 6 85 preferably hinged to the bottom wall. Located within the cabinet is a meter circuit controlling appliance represented as an entirety by 7. The details of the appliance 7 can be varied widely, but the appliance as 90 shown includes terminals 8, 8 and 9 adapted to be connected with incoming service wires, terminals 10, 10 and 11, 11 adapted to be connected with the meter and terminals 12, 12 and 9^a adapted to be connected with the 95 load conductors. Interposed between the terminals 8, 8 and 10, 10 are fuse contacts 13, 13 and also interposed between these terminals are switch blades (not shown) which are operable by means of a handle 14 located 100 on the exterior of the cabinet.

The meter is represented at 15 and preferably this is mounted in immediate co-operative relationship with the cabinet, a part of the meter projecting downward through 105 an opening provided therefor in the end wall 5 of the cabinet. Thus the conductor wires connecting the appliance 7 with the meter are entirely enclosed within the cabinet.

The several terminals already referred 110 to are preferably provided with auxiliary contacts adapted for the attachment of meter testing devices as well known in the art, and preferably the contacts 11, 11 and 12, 12 are respectively connected by means of 115 movable testing blades 15^a, 15^a.

It will be seen that when the cover 6 is in closed position and sealed, the entire circuit controlling appliance 7, together with the fuses at 13, 13 and the several conductors 120 and terminals are entirely protected from unauthorized access by a customer. However, the switch handle 14 being located outside of the cabinet, is accessible to the customer for opening or closing the circuit. 125

In accordance with the invention I provide a block preferably formed mainly or entirely of insulating material and adapted to be mounted externally of the cabinet and immediately adjacent a wall of the cabinet 130

so as to at least partly close an opening therein. As shown in Figs. 1 and 3 to 6, there is a block 16 which is adapted to be mounted adjacent the bottom wall 4 of the cabinet so as to at least partly close a circular opening therein, and preferably it is constructed to close the front portion of the opening leaving an unobstructed space at or near the rear of the opening. As shown the block 16 is provided with a U-shaped recess 17 closed at the front and at both sides and open at the rear end and at the end adjacent the cabinet. This recess registers with the opening in the cabinet wall when the block is in place and provides space for conductor terminals as will presently appear.

Preferably there is a projection on the block which is adapted to extend into the opening in the cabinet wall, the aforesaid recess 17 being located to extend into the projection. As illustrated in Figs. 3 and 4 the projection 18 may be formed integrally with the block and it is of such size and shape as to entirely close the opening in the cabinet wall except for the recess 17. The projection 18 is preferably utilized as a means for holding the block in place, means being provided for engaging the projection for this purpose inside of the cabinet. The projection is shown as being formed with external screw threads 19 adapted to be engaged by a nut for the purpose not only of holding the block in place on the cabinet wall but also of forcing it toward the cabinet with a clamping action.

Instead of making the projection 18 integral with the main body of the block, as shown in Figs. 3 and 4, I have found it ordinarily preferable to make the projection 40 separate and to form it of metal or other material less fragile than the porcelain of which the block is usually formed. In Figs. 1, 5, 6 and 7 I have shown a projection in the form of a bushing 20 which is separate from the main body of the block. Suitable means are provided as will hereafter be described in detail for connecting the body of the block with the bushing. The bushing 20 is externally threaded at 21 so as to be adapted to be engaged by a nut 22. When the separate bushing 20 is provided, the body of the block is preferably provided with a smaller projection 18^a which is located inside of the bushing and which preferably extends nearly to the upper end thereof.

Preferably in order that the block may be held against turning about the axis of the projection it is so formed that its rear face is closely adjacent the plane of the rear wall of the cabinet, as illustrated in Figs. 8 and 9. The result is that when the cabinet is mounted on a wall or panel having a flat supporting surface the block is held in such relation to the said wall or panel that any con-

siderable amount of turning about the axis of the projection is prevented.

As already stated, the fuse receiving contacts are so located as to be accessible externally of the cabinet when the block is in place. This makes the fuses available for renewal or replacement by the customer, notwithstanding the fact that the service fuses at 13, 13, and in fact the entire circuit controlling appliance 7 and its conductors, may be sealed against access as already explained. The fuse receiving contacts may be of any usual or preferred type and the invention in its broader aspects is not limited to contacts of any one type. I preferably construct and arrange the receiving contacts so that the fuses are removable in a direction at a considerable angle from the plane of the back of the cabinet so as to be more easily accessible from the front than they would be if they were removable in a direction parallel with the said plane as has heretofore been the practice. I have shown contacts adapted for the reception of fuses of the screw plug type, and when provision is made for receiving fuses of this type, the fuses are held with their axes at a considerable angle from the plane of the back of the cabinet. Preferably, and as shown, the axes are perpendicular to the plane of the back of the cabinet and parallel to the cabinet wall which supports the attachment.

Figs. 1, 7, 8 and 9 show in detail an attachment having four pairs of contacts for receiving screw plug fuses, these being represented at 23, 23 and 24, 24. These are arranged with their axes positioned as described and with two pairs at each side of the center of the block.

For electrically connecting one contact of each pair with a conducting part of the appliance within the cabinet at least one terminal is provided as already stated. Preferably when there are two or more pairs of contacts, two such terminals are provided in order that the attachment may form a part of a three wire circuit, some of the pairs of contacts being connected with one terminal and the remaining ones with the other. As shown in Fig. 9, the center contacts of the pairs 23, 23 are connected together by a conducting strip 25 in a groove at the back of the block. The center contacts of the pairs 24, 24 are similarly connected together by a conducting strip 26 in another groove at the back of the block. The said grooves communicate with the U-shaped recess 17 and the before mentioned terminals are respectively connected with these strips 25 and 26 and are positioned to extend into the cabinet when the block is in place, so as to be available for establishing a connection with conducting parts of the said appliance within the cabinet.

Preferably each of the terminals is permanently connected to the block and with the

- corresponding fuse contact or contacts and is in the form of a continuous terminal conductor long enough to extend through the said opening in the cabinet wall and to directly and of itself engage and connect with a conducting part of the appliance without the use of any separate wires or other intermediate conductors. These terminals are included as composite elements of the complete fuse block attachment at the time of its manufacture and prior to its connection with the cabinet. They are not intended to be removed or disconnected at any time. Preferably, and as shown, the terminals are in the form of flexible wires 27 and 28 which are permanently connected respectively with the strips 25 and 26 and which are located in the recess 17 so as to extend through the bushing 20 and into the cabinet when the block is in place.
- 20 These flexible terminal wires may be respectively connected directly to the terminals 12, 12 of the appliance 7 as shown in Fig. 1. It will be observed that the connection of each terminal to the block and to the corresponding fuse contact or contacts is so located as to be inaccessible when the block is in place, and it will be further observed that the said connection and also all portions of the terminal outside of the cabinet are entirely covered 25 by the front face of the block. Preferably the grooves in the back of the block containing the strips 25 and 26 and containing the connection with the terminal wires 27 and 28 are filled with sealing wax or other similar material as indicated at 29. As shown the sealing wax also extends into the recess 17.
- In order to provide a neutral path or connection for the attachment I preferably provide another terminal conductor similar in function and in form to those already described. When the terminal conductors are in the form of flexible wires as shown, a neutral terminal conductor 30 is located in the recess 17 in grouped relation with the other conductors and extends into a groove in the back of the block, as shown in Fig. 8. As shown in Fig. 1 this terminal conductor 30 may be directly connected to the neutral terminal 9^a on the appliance 7.
- 50 When flexible conductors are provided and when a metal bushing 20 is provided I preferably provide insulating means, supplemental to their own insulation, for holding the conductors out of contact with bushing at the rear where the recess 17 is open. As shown in Fig. 10 this means is a plate or disk 31 of insulating material having one or more closed-side openings through which the conductors extend. This disk engages the end of the projection 18^a and is seated within the bushing 20 which may be provided with an inward extending flange to hold the disk in place.
- 65 As shown in Figs. 11 and 12 the two terminals 27 and 28 may consist of a single con-

tinuous piece of wire permanently connected to the block at its ends as described. When a continuous or looped terminal is thus provided a further advantage is obtained in that the attachment is more readily adapted 70 for use when desired as a part of a two wire circuit. For a three wire circuit the two terminals are cut apart and connected as shown in Fig. 1; but for a two wire circuit the two terminals 27 and 28 are left intact 75 and are connected to one of the terminals 12 as shown in Fig. 12. In this case the terminal 30 is connected to the other terminal 12. This looped arrangement makes it possible for the installing workman to connect both 80 terminals simultaneously, not only saving time but providing a neater and better connection.

The remaining contacts of the pairs of fuse contacts, in the construction shown these being the outer threaded shells, are connected respectively to circuit wire connecting terminals. Preferably and in accordance with one phase of the invention these terminals are positioned to be accessible from the outside of the cabinet when the block is in place 85 and they are adapted for the direct connection of circuit wires located entirely outside of the circuit. These terminals are shown at 32, 32 and 33, 33. The outside location of 90 these terminals makes it unnecessary to carry the branch circuit connections back into the cabinet as was necessary in the constructions shown in my aforesaid patents.

When a neutral connection is provided 100 there is a common neutral terminal 34 for the wires of all of the branch circuits. As shown this neutral terminal 34 is located in a recess in the front of the block and is connected by means of a screw 35 with the terminal conductor 30. Preferably the joint between the screw 35 and the conductor 30 is covered with sealing wax or similar material as shown at 29.

I preferably provide means such as a plate 110 for covering the connections for the terminals 27, 28 and 30 and rendering such connections inaccessible even when the attachment is not connected to a cabinet. By preference this plate constitutes the rear wall of 115 a box 36 which encloses at least a part of, and ordinarily a major portion of, the block and parts carried thereby.

The box 36, as shown, is constructed to enclose substantially the entire block 16, but it 120 is provided with an opening in the top wall through which the bushing 20 and the projection 18^a extend. The box has a movable, preferably hinged, cover 37 which permits access to the fuses and other parts of the device. The plate constituting the rear wall of the box is rigidly connected to the block as for instance by screws 38, 38. The bushing 20 has a collar 39 thereon which engages the inner surface of the top wall of the box, and 125

thus the box serves as a means for connecting the bushing to the body part of the block. Preferably the collar 39 is square, or otherwise non-circular, and fits a similarly formed recess in the top of the body part of the block. In this way the bushing is interlocked with the body part of the block to prevent rotation. The bushing 20 is engaged by the nut 22 as already described and these parts, therefore, constitute common means for clamping both the block and the box to the cabinet wall. The rear wall of the box is preferably flush with the rear wall of the cabinet when the attachment is in place and thus both the box and the block are held against rotation about the axis of the bushing.

The box is provided with conveniently located knock-outs which may be removed to permit the passage of branch circuit conductor wires connected with the terminals 32, 32, 33, 33 and 34. As shown conduit pipes are connected to the box at the several knock-out openings.

The box 36 may be provided with a removable auxiliary interior cover 40 as shown in Figs. 7, 8, 9 and 11. This cover serves as a so-called dead front to prevent accidental contact with the terminals and conductors inside the box, and it is provided with openings through which the fuses may be removed or put in place. The details of the construction and mounting of the cover 40 form no part of the present invention.

Preferably small insulating bushings 40^a are mounted in holes in the cover 40, these bushed holes providing means whereby test wires may be inserted to engage the respective wire receiving terminals on the block.

In Figs. 13 and 14 I have shown an embodiment of the invention adapted for use when only two branch circuits are required.

The construction is otherwise similar to that shown in Figs. 1, 2 and 5 to 12 and repetition of the detailed description is unnecessary. The attachment comprises a block 16^a similar to the block 16 except that it is provided with only two pairs of fuse receiving contacts 23^a and 24^a. Terminal conductors 27^a, 28^a and 30^a are provided similar to the conductors 27, 28 and 30 and there are also provided load wire receiving terminals 32^a, 33^a and 34^a. The block is enclosed in a box 36^a similar to the box 36 except as to size.

In Figs. 15 to 19 I have shown an attachment which is different in appearance and in details of construction from the attachments already described, but which nevertheless embodies some of the features of the invention.

The attachment comprises a block 41 having a projection 42 which is shaped and adapted to extend through and fit an open-side notch in one side wall of the cabinet and extending from the front thereof. Carried by the block are one or more pairs of fuse re-

ceiving contacts, the said contacts being accessible from the outside of the cabinet when the block is in place. As shown, there are two pairs of contacts 43, 43 adapted for receiving fuses of the screw plug type with their axes parallel to the supporting wall of the cabinet.

Connected respectively with the pairs of fuse receiving contacts are terminals 44, 44 which extend inward through recesses 45, 45 in the projection 42. In the present instance the terminals are not adapted to directly and of themselves engage and connect with a conducting part on the appliance within the cabinet, but they are nevertheless so positioned as to be available for establishing connections with such conducting parts.

Also connected respectively with the fuse receiving contacts in series with the said terminals 44, 44 are terminals 46, 46 which are mounted on the block in position to be accessible from the outside of the cabinet when the block is in place so as to be adapted for the direct connection of branch circuit conductor wires located entirely outside of the cabinet. Wire receiving holes or recesses 47 extend through the block adjacent the terminals 46, 46.

Connected with the block 41 is a box 48 which is in position to engage the supporting wall of the cabinet when the block is in normal position as shown. The box 48 does not enclose the entire block, but it provides a chamber adjacent the rear surface of the block, this chamber being adapted for the reception of branch circuit wires which are connected to the said terminals 46, 46. The box 48 is provided with one or more knock-outs adapted to be used for the admission of the said wires to the box and for the connection of conduit pipes.

As shown in the drawings the box 48 serves not only to enclose the end parts of the circuit wires as stated, but it also serves as a means for the attachment of the block to the cabinet wall. The cabinet wall and the adjacent wall of the box are provided with screw holes so that a screw 49 may be inserted for the purpose of clamping the box against the cabinet wall and thus holding the entire device in place in the openside notch. The screw 49 thus constitutes a common means for clamping both the box and block to the cabinet wall.

Preferably a hinged cover 57 is provided at the front side of the block for enclosing the fuses.

As shown in Fig. 15 the wiring is for a two-wire system and the attachment provides fuses in both legs of a branch circuit. Two attachments are shown secured to one cabinet in order to provide for two branch circuits. It will be understood, however, that different wiring connections may be provided so that a single attachment may provide a fuse in one

leg of each of two branch circuits, whether two-wire or a three-wire system be used. When the attachment is so wired a neutral wire may be led into the box 48 through a notch or recess 58 in the projection 42.

5. What I claim is:

1. A fuse block attachment for an electric appliance containing cabinet comprising in combination, a block adapted to be externally mounted immediately adjacent a wall of the said cabinet so as to at least partly close an opening therein, a pair of complementary fuse receiving contacts on the block accessible externally of the cabinet when the block is in place as aforesaid, a circuit wire connecting terminal electrically connected with one of the fuse receiving contacts on the block, and a continuous conductor having a permanent electrical connection with the other fuse receiving contact on the block so as to be included as a composite element of the complete fuse block attachment prior to its connection with the said cabinet and being long enough to extend through the said opening in the cabinet wall and to directly and of itself engage and connect with a conducting part of the appliance within the cabinet when the block is in place as aforesaid.
2. A fuse block attachment for an electric appliance containing cabinet comprising in combination, a block adapted to be externally mounted immediately adjacent a wall of the said cabinet so as to at least partly close an opening therein, a pair of complementary fuse receiving contacts on the block accessible externally of the cabinet when the block is in place as aforesaid, a circuit wire connecting terminal electrically connected with one of the fuse receiving contacts on the block, a continuous terminal conductor having a permanent electrical connection with the other fuse receiving contact on the block so as to be included as a composite element of the complete fuse block attachment and being long enough to extend through the said opening in the cabinet wall and to directly and of itself engage and connect with a conducting part of the appliance within the cabinet when the block is in place as aforesaid, and a box connected with the block so as to enclose at least a part thereof and serving to render the electrical connection between the said conductor terminal and the corresponding fuse contact inaccessible prior to the connection of the attachment to the said cabinet.

3. A fuse block attachment for an electric appliance containing cabinet comprising in combination, a block adapted to be externally mounted immediately adjacent a wall of the said cabinet so as to at least partly close an opening therein, a pair of complementary fuse receiving contacts on the block accessible externally of the cabinet when the block is in place as aforesaid, two circuit wire connecting terminals of which one is electrically con-

nected with one of the fuse receiving contacts on the block, and two continuous terminal conductors having electrical connections respectively with the other fuse receiving contact on the block and with the remaining wire connecting terminal which connections are inaccessible when the block is in place as aforesaid, both of the said terminal conductors being included as composite elements of the complete fuse block attachment prior to its connection with the said cabinet and all being long enough to extend through the said opening in the cabinet wall and to directly and of themselves engage and connect with conducting parts of the appliance within the cabinet when the block is in place as aforesaid.

4. A fuse block attachment for an electric appliance containing cabinet comprising in combination, a block adapted to be externally mounted immediately adjacent a wall of the said cabinet so as to at least partly close an opening therein, the said block having a narrow recess in the back thereof open at one end so as to register with the said opening in the cabinet wall, a pair of complementary fuse receiving contacts on the block accessible externally of the cabinet when the block is in place as aforesaid, a circuit wire connecting terminal electrically connected with one of the fuse receiving contacts on the block, and a continuous terminal conductor having a permanent electrical connection with the other fuse receiving contact on the block so as to be included as a composite element of the complete fuse block attachment prior to its connection with the said cabinet, the said terminal conductor being positioned in the said recess so as to extend through the said opening in the cabinet wall when the block is in place as aforesaid and being long enough to directly and of itself engage and connect with a conducting part of the appliance within the cabinet.

5. A fuse block attachment for an electric appliance containing cabinet comprising in combination, a block adapted to be externally mounted immediately adjacent a wall of the said cabinet so as to at least partly close an opening therein, a pair of complementary fuse receiving contacts on the block accessible externally of the cabinet when the block is in place as aforesaid, a circuit wire connecting terminal electrically connected with one of the fuse receiving contacts on the block, and a continuous flexible terminal conductor wire having a permanent electrical connection with the other fuse receiving contact on the block so as to be included as a composite element of the complete fuse block attachment prior to its connection with the said cabinet and being long enough to extend through the said opening in the cabinet wall and to directly and of itself engage and connect with a conducting part of the appliance within the cabinet.

cabinet when the block is in place as aforesaid.

6. A fuse block attachment for an electric appliance containing cabinet comprising in combination, a block adapted to be externally mounted immediately adjacent a wall of the said cabinet so as to at least partly close an opening therein, two pairs of complemental fuse receiving contacts on the block accessible externally of the cabinet when the block is in place as aforesaid, two circuit wire connecting terminals each electrically connected with one of the fuse receiving contacts of one of the pairs of such contacts on the block, and a continuous flexible looped terminal conductor wire having permanent electrical connections at its respective ends with the other fuse receiving contacts of the pairs of such contacts on the block, the said terminal conductor wire being included as a composite element of the complete fuse block attachment prior to its connection with the said cabinet and being long enough to extend through the said opening in the cabinet wall and to directly and of itself engage and connect with one or more conducting parts of the appliance within the cabinet when the block is in place as aforesaid and the said terminal conductor wire being adapted to be cut between its ends for a three wire circuit or to remain intact between its ends for a two wire circuit.

7. A fuse block attachment for an electric appliance containing cabinet comprising in combination, a block adapted to be externally mounted immediately adjacent a wall of the said cabinet so as to at least partly close an opening therein, two pairs of complemental fuse receiving contacts on the block accessible externally of the cabinet when the block is in place as aforesaid, three circuit wire connecting terminals of which two are electrically connected respectively with two of the fuse receiving contacts of the two pairs of such contacts on the block, a continuous flexible looped terminal conductor wire having permanent electrical connections at its respective ends with the other fuse receiving contacts of the pairs of such contacts on the block, and another continuous flexible conductor wire having a permanent electrical connection at one end with the remaining circuit wire connecting terminal, both of the said terminal conductor wires being included as composite elements of the complete fuse block attachment prior to its connection with the said cabinet and both of them being long enough to extend through the said opening in the cabinet wall and to directly and of themselves engage and connect with conducting parts of the appliance within the cabinet when the block is in place as aforesaid and the first of the said terminal conductor wires being adapted to be cut between its ends for a three wire circuit or to remain intact between its ends for a two wire circuit.

8. A fuse block attachment for an electric appliance receiving cabinet comprising in combination, a block adapted to be externally mounted immediately adjacent a wall of the cabinet so as to at least partly close an opening therein, a pair of complemental fuse receiving contacts on the said block accessible externally of the cabinet when the block is in place as aforesaid, a terminal connected with one of the fuse receiving contacts and positioned on the block to extend through the said opening and to be available for establishing a connection with a conducting part of the appliance within the cabinet when the block is in place as aforesaid, and a second terminal on the block connected with the other fuse receiving contact and positioned to be accessible from the outside of the cabinet when the block is in place as aforesaid so as to be adapted for the direct connection of a circuit conductor wire located entirely outside of the cabinet.

9. A fuse block attachment for an electric appliance receiving cabinet comprising in combination a block adapted to be externally mounted immediately adjacent a wall of the cabinet so as to at least partly close an opening therein, a pair of complemental fuse receiving contacts on the said block accessible externally of the cabinet when the block is in place as aforesaid, a terminal connected with one of the fuse receiving contacts and positioned on the block so as to be adapted to extend through the said opening and to be available for establishing a connection with a conducting part of the appliance within the cabinet when the block is in place as aforesaid, a second terminal on the block connected with the other fuse receiving contacts and positioned to be accessible from the outside of the cabinet when the block is in place as aforesaid so as to be adapted for the direct connection of a circuit conductor wire located entirely outside of the cabinet, and a box connected with the block and substantially enclosing the said block and also enclosing the fuse contacts and the last said terminals.

10. A fuse block attachment for an electric appliance receiving cabinet comprising in combination a block adapted to be externally mounted immediately adjacent a wall of the cabinet so as to at least partly close an opening therein, a pair of complemental fuse receiving contacts on the said block accessible externally of the cabinet when the block is in place as aforesaid, a continuous terminal conductor having a permanent electrical connection with one of the fuse receiving contacts so as to be included as a composite element of the complete fuse block attachment prior to its connection with the said cabinet and being long enough to extend through the said opening in the cabinet wall and to directly and of itself engage and connect with a conducting part of the appliance within the cabinet.

when the block is in place as aforesaid, and a second terminal on the block connected with the other fuse receiving contact and positioned to be accessible from the outside of the cabinet when the block is in place as aforesaid so as to be adapted for the direct connection of a circuit conductor wire located entirely outside of the cabinet.

11. The combination of a circuit controlling appliance and the service and load conductors therefor, a cabinet enclosing the appliance and conductors and adapted to be sealed for protecting them against unauthorized access, a block, means for externally securing the block to a wall of the cabinet adjacent an opening therein so as to at least partly close the same, a pair of complementary fuse receiving contacts on the said block accessible externally of the cabinet, a terminal connected with one of the fuse receiving contacts and positioned on the block to extend through the said opening and to be available for establishing a connection with a conducting part of the appliance within the cabinet, and a second terminal on the block connected with the other fuse receiving contact and positioned to be accessible from the outside of the cabinet so as to be adapted for the direct connection of a circuit conductor wire located entirely outside of the cabinet.

12. A fuse block attachment for an electric appliance receiving cabinet comprising in combination, a block adapted to be externally mounted immediately adjacent a wall of the cabinet so as to at least partly close an opening therein, a box enclosing a major portion of the said block, a common means for clamping both the block and the box to the said wall of the cabinet, a pair of fuse receiving contacts carried by the said block inside the box and accessible externally of the cabinet when the block and box are in place as aforesaid, a terminal connected with one of the fuse receiving contacts and positioned on the block so as to be adapted to extend through the said opening in the cabinet wall and to be available for establishing a connection with a conducting part on the appliance within the cabinet, and a second terminal inside the box connected with the other fuse receiving contact and positioned to be accessible from the outside of the cabinet so as to be adapted for the direct connection of a conductor wire.

13. A fuse block attachment for an electric appliance receiving cabinet comprising in combination, a block adapted to be externally mounted immediately adjacent a wall of the cabinet and having a projection extending into and approximately fitting an opening therein, a box enclosing a major portion of the said block and having an opening in one wall through which the said projection extends, means adapted to be located within the cabinet for engaging the projection to hold

both the block and the box in fixed relation to the said wall of the cabinet, a pair of fuse receiving contacts carried by the said block inside the box and accessible externally of the cabinet when the block and box are in place as aforesaid, a terminal connected with one of the fuse receiving contacts and positioned on the block so as to be adapted to extend through the said opening in the cabinet wall and to be available for establishing a connection with a conducting part on the appliance within the cabinet, and a second terminal connected with the other fuse receiving contact and adapted for the connection of a conductor wire.

14. A load circuit fuse attachment for an electric appliance receiving cabinet comprising in combination, a block body adapted to be externally mounted immediately adjacent a wall of the cabinet so as to at least partly close an opening therein, a pair of fuse receiving contacts on the said block body accessible externally of the cabinet when the body is in place as aforesaid, a terminal connected with one fuse receiving contact and positioned on the body so as to be adapted to extend through the said opening in the wall and to be available for establishing a connection with a conducting part on the appliance within the cabinet, a second terminal on the block body connected with the other fuse receiving contact and adapted for the connection of a conductor wire, a bushing separate from the block body surrounding the first said terminal and adapted to project through the said opening in the cabinet wall, means for connecting the bushing to the body, and means for engaging the bushing inside of the cabinet to secure the body in place as aforesaid.

15. A load circuit fuse attachment for an electric appliance receiving cabinet comprising in combination, a block body adapted to be externally mounted immediately adjacent a wall of the cabinet so as to at least partly close an opening therein, a pair of fuse receiving contacts on the said block body accessible externally of the cabinet when the body is in place as aforesaid, a terminal connected with one fuse receiving contact and positioned on the body so as to be adapted to extend through the said opening in the cabinet wall and to be available for establishing a connection with a conducting part on the appliance within the cabinet, a second terminal on the block body connected with the other fuse receiving contact and adapted for the connection of a circuit conductor wire, a box enclosing a major portion of the block body and also enclosing the fuse contacts and the last said terminal, the said box having an opening in one wall adapted to register with the opening in the cabinet wall, a bushing separate from the block body surrounding the first said terminal and extending

through the opening in the box wall and being adapted to project through the opening in the cabinet wall, the said bushing having a collar inside of the box engaging both the block body and the inner surface of the adjacent box wall, means for connecting the box to the body thus indirectly connecting the bushing to the body, and means for engaging the bushing inside of the cabinet to secure both the body and the box in place.

16. A load circuit fuse attachment for an electric appliance receiving cabinet comprising in combination, a block adapted to be externally mounted immediately adjacent a wall of the cabinet and having an attaching means adapted to extend into an opening therein, a pair of fuse receiving contacts on the said block accessible externally of the cabinet when the block is in place as aforesaid, a terminal connected with one fuse receiving contact and positioned on the block so as to be adapted to extend through the said opening in the wall and to be available for establishing a connection with a conducting part on the appliance within the cabinet, a second terminal on the block connected with the other fuse receiving contact and adapted for the connection of a conductor wire, and a box enclosing a major portion of the block and also enclosing the fuse contacts and the last said terminals, the said box having an opening therein for the said attaching means and being constructed so that its rear wall is flush with the rear wall of the cabinet when the attachment is in place thereby preventing rotation of the box and block about the axis of the attaching means when the cabinet is mounted on a flat supporting wall.

17. The combination of a circuit controlling appliance and the service and load conductors therefor, a cabinet enclosing the appliance and conductors and adapted to be sealed for protecting them against unauthorized access, a block externally mounted immediately adjacent a wall of the cabinet so as to at least partly close an opening therein, a box enclosing a major portion of the said block and having one wall in contact with the said wall of the cabinet, there being an opening in the last said box wall registering with the opening in the cabinet wall, a common means for clamping both the block and the box to the said wall of the cabinet, a pair of fuse receiving contacts carried by the said block inside the box and accessible externally of the cabinet, a terminal connected with one of the fuse receiving contacts and extending through the said openings in the box and cabinet walls, the said terminal being adapted for establishing a connection with a conducting part on the appliance within the cabinet, and a second terminal inside the box connected with the other fuse receiv-

ing contact and positioned to be accessible from the outside of the cabinet so as to be adapted for the direct connection of a circuit conductor wire.
